UNITED STATES PATENT OFFICE.

HUGO NOACK, OF STAMFORD, AND HERMANN MARING, OF DARIEN, CONNECTICUT.

WATERPROOF BUILDING-BLOCK.

No. 865,654.

Specification of Letters Patent.

Patented Sept. 10, 1907.

Application filed March 22, 1906. Serial No. 307,428.

To all whom it may concern:

Be it known that HUGO NOACK, a citizen of the United States, and HERMANN MARING, a subject of the Emperor of Germany, residing, respectively, at Stamford and Darien, county of Fairfield, State of Connecticut, have invented a new and useful Waterproof Building-Block, of which the following is a specification.

This invention relates to the manufacture of artificial stone or concrete building blocks and has for its object to provide building blocks which shall be light and inexpensive to produce, durable, easy to lay and thoroughly water-proof in use.

It has heretofore been a serious objection to the use of artificial stone or concrete building blocks that no matter of what material they were made or how thick, they were not impervious to moisture.

Our present invention enables us to produce building blocks of this character so constructed as to wholly prevent the passage of moisture through them, thus adapting artificial stone building blocks to general use both in the foundations and walls of buildings and enabling us to erect very solid and strong walls with any required ornamentation and at a minimum expense.

25 This we accomplish by the construction and combination of parts substantially as hereinafter described and claimed.

In the accompanying drawing forming a part of this specification, Figures 1, 2 and 3 are plan views of sections of walls, illustrating the use of our novel building blocks, these views illustrating slightly varying styles of blocks in which the inner and outer walls and the cross pieces are molded integral. Fig. 4 shows the structure of the wall in which the bases of the inner 35 members of the blocks lie higher than the bases of the outer members so that the horizontal joints in the completed walls are not opposite each other.

It is to be understood that the outer walls of the blocks may be molded to any required ornamental design or may be given a rough ashler finish.

10 denotes the inner walls of the blocks, 11 the outer walls, 12 cross pieces, 13 spaces bounded by the inner and outer walls and the cross pieces and 21 spaces between the cross pieces.

14 indicates horizontal joints between the blocks 45 and 15 vertical joints between the blocks.

The walls and cross pieces may be made of any suitable material for artificial stone, it being wholly unimportant, so far as the principle of the invention is concerned, of what material or mixture the blocks and 50 cross pieces are molded.

The forms illustrated in Figs. 1, 2, and 3 differ only in the number of cross pieces in each block and the size and number of the spaces between the cross pieces. An important feature of our improved construction is 55 that the cross pieces extend from the inner walls downward and outward to the outer walls, and the outer member of each block is in a plane below that of the inner member when set in a wall and the essential feature is that the cross pieces in all the forms extend 60 downward and outward obliquely to the horizontal plane and are provided with spaces 21 between them, and that the cross pieces are rigid with the wall members. The result is that any moisture that may penetrate the outer wall will work downward by gravity and 65 will not follow the oblique cross pieces upward, so that in use the inner walls remain perfectly dry.

Having thus described our invention we claim:

1. A building block consisting of inner and outer wall members and a continuous connecting cross piece extending obliquely to the horizontal plane between said wall members and of the same material as the wall members and rigid therewith, said two wall members being stepped in relation to each other, whereby they occupy different horizontal planes when the block is set in a wall with its 75 surfaces of greater area in vertical position.

2. A building wall consisting of blocks each comprising an inner and an outer wall member and a continuous connecting cross piece extending downward and outward between said wall members leaving spaces between the cross pieces, said cross piece being of the same material as the wall members and rigidly connecting them, the base of the inner wall member of each block being higher than the base of the outer wall member so as to place the outer horizontal joints out of alignment with the inner 80 horizontal joints.

In testimony whereof we affix our signatures in presence of two witnesses.

HUGO NOACK.
HERMANN MARING.
